DISTANCE-TYPE RELAY WITH CURRENT-COMPENSATED VOLTAGE RESTRAINT

William K. Sonnemann, Roselle Park, N. J., assignor to Westinghouse Electric Corporation, East Pittsburgh, Pa., a corporation of Pennsylvania

Application February 16, 1945, Serial No. 578,263

4 Claims. (Cl. 175—294)

1

My invention relates to adjustable distance-type relays having modified impedance characteristics which can be readily adjusted. This relay is adapted to be utilized on alternating-current lines for the purpose of detecting faults thereon.

Recent trends in the art of high-speed relaying for transmission lines, and more particularly for the so-called long transmission lines, have indicated the need for high-speed impedance relays having modified characteristics, that is, having predetermined directional, as well as impedance, characteristics. The response-circle, representing the locus of the line-impedance values at the balance-point of such a relay, when plotted on rectangular coordinates of the line-resistance R and the line-reactance X , will have a center which is, in general, displaced from the origin and adjustable in position, and a radius which is also adjustable in magnitude. If these adjustments are properly calibrated, and of such nature that they can readily be made by the user of the relay, they thus afford a means whereby the particular exigencies of each protective system may be properly adjusted to the transmission system to which it applies.

An object of my invention is to provide a new and improved means whereby these adjustments may be separately and independently made, so that a calibrated adjustment may be made as to the circle-radius, or as to either the R or X coordinates of the center of the circle, without substantially changing the other two adjustments or settings; or the position of the center may be fixed by independently adjusting the angle of the line along which the center is displaced from the origin, and the amount or distance of such displacement of the center from the origin.

A further object of my invention is to provide a relay of the differential type, that is, a relay having an operating force and a restraining force, and means for causing the operating force to be dependent solely upon the magnitude of the line-current, but variable or adjustable in its response, while causing the restraining force to be responsive to a current-compensated line-voltage, which is equal to the vectorial sum of an alternating-current function of a line-derived voltage, an alternating-current function of a line-derived current times a variable resistance, or its equivalent, and an alternating-current function of a line-derived current times a variable reactance, or its equivalent. The energization of the relay is such that the adjustability of the operating-force response affords a means for ad-

2

justing the length of the radius of the response-circle, without substantially affecting the position of the center of the circle, while the adjustments of the variable resistance and the variable reactance respectively control the R and X coordinates of the center of the response-circle, without materially affecting its radius.

A further object of my invention relates to the provision of means for both reversing and adjusting the magnitude of both the in-phase and the out-of-phase components of the current-responsive compensator, independently of each other, so that the center of the response-circle can be readily located in any position in any one of the four quadrants.

With the foregoing and other objects in view, my invention consists in the apparatus, combinations, systems, parts, and methods hereinafter described, and claimed, and illustrated in the accompanying drawing, wherein:

Fig. 1 is a diagrammatic view of circuits and apparatus illustrating the connections for a phase-A, phase-fault relay embodying my invention.

Fig. 2 is a response-circle diagram illustrating the invention, and

Fig. 3 is a diagrammatic view of parts of the energizing circuits of a modified form of embodiment of my invention.

In Fig. 1, I have illustrated my invention as being applied to the protection of a three-phase transmission line 5, the three phases of which are indicated at A, B and C. The line 5 is connected to a bus 6. My invention is shown, by way of illustration, as applied to a phase-fault relay, shown at 7, for responding to phase-A faults, or, more accurately, faults involving phases A and B of the transmission system. Only one such relay is illustrated, as I show relays for but a single phase. Ordinarily there would be several such relays, one for each phase, and also a ground-fault relay, or else some special phase-sequence energization-means whereby a single relay is made to respond to a plurality of types of faults on different phases, all of which things are well known in the art.

The relay 7 is intended to be representative or symbolic of any differential type of relay, by which I mean a relay which has an operating force opposed by a restraining force. The particular differential-type relay 7 which is shown in Fig. 1 is of the balanced-beam type, having an operating coil or winding 8, and two split-phase restraining coils or windings 9 and 10. The magnetizing currents in the two restraint-wind-

ings 9 and 10 are approximately 90° out of phase with each other, this dephasing being accomplished by means of a capacitor C in series with the winding 10, the two windings 9 and 10 being energized in parallel from a common energizing-circuit having a voltage $\dot{E}_R$. This is a well-known means for obtaining a substantially steady or non-pulsatory restraining-force for insuring the proper operation of the relay.

The relay 1 is illustrated as having a single make-contact 11 on the operating end of the beam. The relaying circuits which are controlled by the make-contact 11 are not shown, as my present invention relates primarily to the means for controlling the closure of these contacts, rather than the relaying system which is chosen to make use of the relay-contacts in the proper protection of the transmission line 5.

The operating coil 8 of the relay is energized by means of a line-derived current $\dot{I}$ which is furnished by any suitable means such as line-current transformers 12. The restraining windings 9 and 10 are energized from a current-compensated line-derived voltage $\dot{E}_R$. The restraint-voltage $\dot{E}_R$ is obtained from a line-derived voltage $\dot{E}$, which is derived by any suitable means such as a potential transformer 13, in series with a compensator comprising an impedance $\dot{Z}_1$ which is traversed by a function of the line-current, produced by means of an auxiliary current-transformer 14 connected in series with the current-supply for the operating coil 8. The auxiliary current-transformer 14 has a primary-winding tap K_1 , or other ratio-adjustment means whereby an adjustable current $K_1\dot{I}$ is supplied to the impedance $\dot{Z}_1$. The impedance $\dot{Z}_1$ consists of a variable resistance R_1 in series with a variable reactance X_1 , the latter being indicated as an inductive reactance, although it could be either inductive or capacitive. The current-compensated voltage-responsive energizing-circuit for producing the restraint-voltage $\dot{E}_R$ thus comprises, in series-circuit relation, the line-derived voltage-source $\dot{E}$, the in-phase compensator-component $K_1\dot{R}_1$, and the out-of-phase compensator-component $jK_1\dot{X}_1$. The combined impedances of the split-phase restraint-windings 9 and 10 are indicated as $\dot{Z}_R$, and the total restraint-winding magnetizing-current is indicated at $\dot{I}_R$.

In Fig. 1, the magnetizing force or ampere-turns on the operating coil 8 are adjustable by means of a tap K on the operating coil 8, or by any equivalent means, so that the operating force is responsive to the magnitude of the quantity $K_1\dot{I}$. The operating and restraining forces of my relay may be responsive to either the first power, or the square, or any other power, of the respective magnetic fluxes on the two sides of the relay, or the two ends of the balanced beam of the relay.

If the line-current $\dot{I}$, as applied to the relay 1, lags the line-voltage $\dot{E}$ by an angle θ , the line-current may be written

$$\dot{I} = I \angle (-\theta) = I e^{-j\theta} = I \cos \theta - jI \sin \theta \quad (1)$$

The line-impedance $\dot{Z} = R + jX$, or the line-ohms to the fault, in terms of the relay-quantities $\dot{E}$ and $\dot{I}$, is

$$\dot{Z} = R + jX = \frac{E}{I} = Z \cos \theta + jZ \sin \theta \quad (2)$$

If the restraint-voltage $\dot{E}_R$ is taken as the ampere-turns on the restraint-side of the differential relay 1, and if the current $K_1\dot{I}$ is taken as the ampere-turns on the operating side of the relay, then the balance-point condition occurs when

$$\dot{E}_R = K_1\dot{I} \angle B \quad (3)$$

where B is the angle by which the restraint-voltage $\dot{E}_R$ leads the line-current $\dot{I}$.

From the energizing circuit for the restraint-windings 9 and 10 in Fig. 1, it is seen that the restraint-voltage $\dot{E}_R$ is

$$15 \quad \dot{E}_R = I_R \dot{Z}_R = \left(\frac{E - K_1 \dot{I} \dot{Z}_1}{\dot{Z}_1 + \dot{Z}_R} \right) \dot{Z}_R \quad (4)$$

Equating Equations 3 and 4, substituting $E = i\dot{Z}$ from Equation 2, and rearranging the terms, we find

$$15 \quad i\dot{Z} - K_1 \dot{I} \dot{Z}_1 = K_1 \dot{I} \left(1 + \frac{\dot{Z}_1}{\dot{Z}_R} \right) \angle B \quad (5)$$

whence the locus of the line-impedance $\dot{Z} = R + jX$, up to the fault, that is, at the balance-point of the relay 1, is found to be

$$20 \quad \dot{Z} = K_1 \dot{Z}_1 + K \left(1 + \frac{\dot{Z}_1}{\dot{Z}_R} \right) \angle B \quad (6)$$

30 If $\dot{Z}_1/\dot{Z}_R$ is negligibly small, as compared to unity, Equation 6 becomes, approximately,

$$25 \quad \dot{Z} = K_1 \dot{Z}_1 + K \angle B \quad (7)$$

which is a circle, as shown at 15 in Fig. 2, having a center (shown at C) which is displaced from the origin O by a distance (impedance-ohms)

$$35 \quad \dot{Z}_0 = K_1 \dot{Z}_1 \quad (8)$$

40 and having a radius

$$40 \quad Q_0 = K \quad (9)$$

The coordinates of the center C are

$$45 \quad R_0 = K_1 R_1 \quad (10)$$

and

$$45 \quad X_0 = K_1 X_1 \quad (11)$$

The slope or angle S_0 of the center-line $\dot{Z}_0$ is

$$50 \quad S_0 = \tan^{-1} \frac{X_0}{R_0} = \tan^{-1} \frac{X_1}{R_1} \quad (12)$$

The distance by which the center C is displaced from the origin O is

$$55 \quad Z_0 = K_1 \sqrt{R_1^2 + X_1^2} \quad (13)$$

In Fig. 2, the response-circle 15 is plotted on rectangular coordinates representing the line-resistance R and the line-reactance X , or jX . If

60 P is any point in the circle 15, the line $OP = \dot{Z}$ represents the line-impedance at the balance-point of the relay. The relay will respond for any line-impedances terminating within the circle 15. For line-impedances terminating outside 65 of the circle 15, the restraining force of the relay exceeds the operating force, and the relay will not respond.

Equations 7, 8 and 9 show that the impedance $\dot{Z}_0$ of the line-ohms up to the center C of the circle 15 is substantially equal to $K_1 \dot{Z}_1$, while the circle-radius CP , or Q_0 , is substantially equal to the variable quantity or ratio K . These variables are all substantially independent of each other.

75 The complete expression for the radius Q_0 of

the circle involves the expression $(1 + \dot{Z}_1 / \dot{Z}_R)$, which is not quite equal to unity. In any practical relay, the ratio $\dot{Z}_1 / \dot{Z}_R$ will actually be rather small compared to unity, and it can be made as small as may be desired, at the expense of a somewhat increased burden on the current-transformers 12. In a practical relay-design for 115 volts, 60 cycles, the restraint-circuit impedance Z_R is of the order of 12,000 ohms, whereas an impedance of the order of 200 or 300 ohms will be ample for Z_1 when used with a suitable ratio K_1 . In the restraint-voltage circuit, the effect of Z_1 in producing a burden is proportional to $K_1 I Z_1$, but in the current-circuit of the line-current transformers 12, the effect of Z_1 in producing an extra burden is proportional to $K_1^2 I^2 Z_1$. It follows that an increase in Z_1 , accompanied by a corresponding decrease in K_1 , retains the same effect in the voltage-circuit, but reduces the burden in the current-circuit. The impedance-values which I have suggested give satisfactory operation, with an acceptable burden on the current-transformers 12, and with a negligible error in the length of the circle-radius, even though the adjustable impedance Z_1 is changed from zero to its maximum value of 200 or 300 ohms.

There are several ways in which my invention can be utilized. Splitting the variable impedance $\dot{Z}_1$ into its in-phase and out-of-phase components R_1 and X_1 , it will be seen, from Equations 7 and 8, that the coordinates of the center C of the response-circle 15 are as stated in Equations 10 and 11, the R-coordinate being $K_1 R_1$, and the X-coordinate being $K_1 X_1$. Thus, leaving the adjustment K_1 alone, on the auxiliary current-transformer 14, the resistance R_1 may be varied or adjusted, in order to fix the R-coordinate R_0 of the center, while the inductance X_1 may be adjusted in order to independently fix the X-coordinate X_0 of the center. It will be readily seen that these two adjustments could be calibrated directly in line-ohms.

The radius Q_0 of the circle 15 can be controlled by varying the relative magnitudes of the responses of the operating force and the restraining force of the relay, with respect to the operating flux and the restraining flux, respectively. Thus, in Equation 3, the variable K may be either retained, as K, on the right-hand side of the equation, or it may be put in the left-hand side of the equation as $1/K$. In the particular type of relay shown in Fig. 1, it is more convenient to adjust the ratio K on the operating end of the relay, than it is to adjust the ratio $1/K$ on the restraint-end thereof, but it will be readily understood that either adjustment may be made. This provides an easy way of independently adjusting the radius of the response-circle 15, without affecting any other characteristic of the relay, so that this adjustment can be calibrated directly in line-ohms, if desired.

There are other ways in which my novel adjustment-means may be utilized. Thus, as shown by Equation 13, the center-displacement is simply the distance Z_0 , which can be controlled by varying the ratio K_1 of the auxiliary current-transformer 14, while keeping the magnitude of the impedance Z_1 constant. The angle S_0 of the center-line $\dot{Z}_0$ can then be changed, as indicated by Equation 12, by changing the phase-angle of the impedance $\dot{Z}_1$, without changing its magnitude Z_1 .

In the foregoing discussion and explanation of my invention, I have described my invention as

being responsive to any suitable line-derived current I , and any suitable line-derived voltage E . I have intended that this discussion should be perfectly general. In the particular relay which is indicated in Fig. 1, the response is to the delta line-current $I_{AB} = I_A - I_B$, and the delta line-voltage E_{AB} . It is to be understood, however, that any other line-derived current and line-derived voltage might have been utilized.

10 Also, while I have shown specific illustrative adjustment-means in Fig. 1, any equivalent adjustment-devices might be utilized.

In some cases, it may be desirable that the effects of the variable resistance R_1 and the variable reactance X_1 shall be separately adjustable in sign or direction as well as in magnitude, each independently of the other, so that the circle-center C may be readily located in any one of the four quadrants of the rectangular system of 20 the coordinates R and X.

Thus, in Fig. 3, I have shown the inductance X_1 as a fixed secondary coil X_1 of a mutual reactance M, having a primary winding 16. The line-derived current I is circulated through the primary from 25 winding 16 of the mutual reactor M, and also through the primary winding 17 of a transformer 18, the secondary winding of which is connected across the resistor R_1 . The primary windings 16 and 17 of the mutual reactor M and the transformer 18 are provided with tap-blocks or other tap-changing means for providing the adjustable taps 19 and 20 on the winding 16, and the adjustable taps 21 and 22 on the winding 17, so that the direction of current-flow can be changed, at will, in either one of these windings, as well as the effective number of turns. Thus, while the resistor R_1 in Fig. 3 and the reactor secondary X_1 in Fig. 3 may both be constant in magnitude, the impedance effects, or the effective impedances, of these elements may be changed, both in magnitude and in sign, by proper choice or adjustment of the adjustable taps 19, 20, 21 and 22.

45 In Fig. 3, a network is shown, for utilizing any voltage-source E, which is applied to the network-terminals 23 and 24, and for utilizing any current-source I, which is applied to the network-terminals 25 and 26. The network produces a current-compensated output-voltage E_R , which 50 is produced across the output-terminals 27 and 28 of the network, while the current-circuit of the network is opened at the output-terminals 29 and 30, so that an operating current I_0 may be circulated in any differentially responsive relay-mechanism, which is broadly indicated by the 55 rectangle 31 in Fig. 3.

The rectangle 31 in Fig. 3 is intended to be representative of any relay circuit, or combination, or means, which compares magnitudes of two electrical quantities, which have been indicated, for convenience in reference, as an operating current I_0 and a restraining voltage E_R , although both quantities might be voltages, or both currents, or any other electrical quantity. The 60 relay 31 has a relay-contact which is symbolically indicated at 32 in Fig. 3, corresponding to the relay-contact 11 in Fig. 1.

65 While I have shown my invention in two different illustrative forms of embodiment, I wish it to be understood that my invention is susceptible of considerable modification, by way of alterations, substitutions, additions, and subtractions, without departing from some of the essential features of the invention. I desire, therefore, that the appended claims shall be accorded

the broadest construction consistent with their language.

I claim as my invention:

1. An adjustable distance-type relay having an operating-circuit means, for producing an operating force responsive to the amount of energization of the operating circuit; a restraint-circuit means, for producing a restraining force responsive to the amount of energization of the restraint circuit; current-responsive energizing-circuit means, for energizing the operating-circuit means so as to be exclusively responsive to a line-derived current; current-compensated voltage-responsive energizing-circuit means, including a resistance, an inductance, a reversible and variable-ratio transformer-means associated with said resistance, and a separate reversible and variable-ratio means associated with said inductance, for energizing the restraint-circuit means in response to the vectorial sum of an alternating-current function of a line-derived voltage, an alternating-current function of a line-derived current times said resistance, and an alternating-current function of a line-derived current times said reactance; and means for varying the relative magnitudes of the responses of the operating force and the restraining force.

2. An adjustable distance-type relay having an operating-circuit means, for producing an operating force responsive to the amount of energization of the operating circuit; a restraint-circuit means, for producing a restraining force responsive to the amount of energization of the restraint circuit; current-responsive energizing-circuit means, for energizing the operating-circuit means so as to be exclusively responsive to a line-derived current; current-compensated voltage-responsive energizing-circuit means, including a resistance, an inductance, a reversible and variable-ratio transformer-means associated with said resistance, and a separate reversible and variable-ratio means associated with said inductance, for energizing the restraint-circuit means in response to the vectorial sum of an alternating-current function of a line-derived voltage, an alternating-current function of a line-derived current times said resistance, and an alternating-current function of a line-derived current times said reactance; and means for varying the magnitude of the response of the operating force.

3. An adjustable distance-type relay having an operating-circuit means, for producing an operating force responsive to the amount of energization of the operating circuit; a restraint-circuit means, for producing a restraining force re-

sponsive to the amount of energization of the restraint circuit; current-responsive energizing-circuit means, for energizing the operating-circuit means so as to be exclusively responsive to a line-derived current; current-compensated voltage-responsive energizing-circuit means for energizing the restraint-circuit means, including an alternating-current source of a line-derived voltage, a serially connected resistance, and a serially connected inductance, a reversible and variable-ratio transformer-means associated with said resistance, a separate reversible and variable-ratio means associated with said inductance, and a variable alternating-current source of a line-derived current associated with said reversible and variable-ratio means for energizing both said resistance and said inductance; and means for varying the relative magnitudes of the responses of the operating force and the restraining force.

4. An adjustable distance-type relay having an operating-circuit means, for producing an operating force responsive to the amount of energization of the operating circuit; a restraint-circuit means, for producing a restraining force responsive to the amount of energization of the restraint circuit; current-responsive energizing-circuit means, for energizing the operating-circuit means so as to be exclusively responsive to a line-derived current; current-compensated voltage-responsive energizing-circuit means for energizing the restraint-circuit means, including an alternating-current source of a line-derived voltage, a serially connected resistance, and a serially connected inductance, a reversible and variable-ratio transformer-means associated with said resistance, a separate reversible and variable-ratio means associated with said inductance, and a variable alternating-current source of a line-derived current associated with said reversible and variable-ratio means for energizing both said resistance and said inductance; and means for varying the magnitude of the response of the operating force.
